UNITED STATES PATENT OFFICE.

CHARLES ALBIN NELSON, OF EAST BERLIN, CONNECTICUT.

ELEVATOR AND CONVEYER APPARATUS FOR BRICK-YARDS.

1,360,010.

Specification of Letters Patent. Patented Nov. 23, 1920.

Application filed April 4, 1919. Serial No. 287,532.

To all whom it may concern:

Be it known that I, CHARLES ALBIN NELSON, a citizen of the United States, residing at East Berlin, in the county of Hartford and State of Connecticut, have invented certain new and useful Improvements in Elevator and Conveyer Apparatus for Brick-Yards, of which the following is a specification.

10 My invention relates to improvements in elevator and conveyer apparatus for brick yards, and the object of my improvement is to produce a combination of elevator apparatus and conveyer apparatus for use in 15 brick yards and that is adapted for use in handling the bricks in unbaked condition intermediate the drying in the yard and the stacking for the baking, or, more particularly, for delivering the dried bricks to the 20 setter for stacking in the usual manner for such baking, the bricks being delivered in groups on pallets, and the pallets after the bricks are removed being returned to the same side of the apparatus from which they 25 were delivered.

In the accompanying drawing:—

Figure 1 is an end elevation, in diagrammatic form, of my improved elevator and conveyer apparatus housed in operative position in a brick yard shed.

Fig. 2 is a similar view, on an enlarged scale, of the apparatus shown in Fig. 1.

Fig. 3 is a side elevation of the same.

Fig. 4 is a side elevation, as viewed from 35 the opposite side from Fig. 3, of the yoke connection and adjacent parts of the delivery roller conveyer for the loaded pallets and the cable return conveyer for the return of the unloaded pallets.

40 Fig. 5 is a plan view of the same.

Fig. 6 is a fragmentary view, on a still further enlarged scale, of the loaded pallet and the pallet hangers.

Fig. 7 is a plan view of the same.

45 My improved elevator and conveyer apparatus for brick yards is positioned so as to extend across the main shed 10 of the brick yard housing in which the bricks after drying are stacked for baking, is supported at 50 one end, at the left end as shown in Fig. 1, on a car 11 for convenience in moving along the length of the main shed 10, the car 11 traveling in the left L 12, and in the right L 13 is an overhead track 14 that supports a carriage 15 so as to be moved to correspond 55 with the shift of the position of the car 11

and which by means of hoisting apparatus 16 serves as the means for support for the other end of the apparatus.

The devices supported by the car 11 comprise a roller gravity conveyer 17 on the left side for receiving the pallets 18 loaded with the dried bricks 16; a second gravity conveyer 20 of the roller form for delivering the unloaded pallets 18 outward from the 60 machine, below the first mentioned conveyer 17; means adjustable as to elevation for supporting the left end of the roller conveyer 21 that extends across the main shed 10 for delivering the loaded pallets to the setters 70 for the removal of the bricks; pivotal supporting means for supporting the left end of a cable conveyer 22 for delivering the unloaded pallets 18 from the right end of the unloading conveyer 21 to the pallet delivery 75 conveyer 20; elevator apparatus 23 for receiving the loaded pallets from the receiving conveyer 17 at a relatively low and fixed level and delivering them to the unloading conveyer 21 at any one of the levels to which 80 it may be set throughout the range of adjustment; a motor 24 for operating the moving parts; and shafting and gearing for operatively connecting the motor 24 with the 85 said moving parts.

The conveyer 21 receives the pallets 18 loaded with bricks 19 at the left end and during the passage from the left toward the right, due to the inclination of the conveyer as provided by the adjustable supporting 90 means at the two ends, the bricks 19 are delivered so as to be accessible to the setters who are building up the stack at any position along the width of the stack, and the adjusting means for the ends mentioned permits of raising the conveyer 21 bodily so as to be accessible for different heights as the stack is built up.

Also, the car 11 at one end of the conveyer 21 and the carriage 15 and track 14 at the 100 other end provide means for shifting the mechanism along the length of the shed 10 to correspond to the building up of the stack along the length thereof.

A pair of standards 25 extend upwardly 105 from the car 11 and serve as supports for the ends of the conveyers and other devices 110 that are supported from the car, and a third standard 26 is also provided for co-operating with the standards 25 for supporting some of the parts.

The standards 25 serve as the main stand-

ards. A pair of shafts 27 supported by the main standards 25 and positioned one above the other, support sprocket gears 28, and a pair of sprocket chains 29 are supported by 5 the sprocket gears 28. The chains 29 support the two ends of a bar 30 or equivalent device that serves as the support for the left end of the upper roller conveyer 21 and the elevation thereof is changed by moving 10 the two sprocket chains 29 in unison.

Movement of the chains 29 is effected by means of a crank 31 supported by one of the main standards 25 and operatively connected to the lower shaft 27 by means of gearing 32 15 of any approved form.

The cable conveyer 22 comprises a pair of side frame members 33 that are supported by their inner or left ends on the shaft 34 and are provided with a shaft 35 at the 20 outer ends or right ends and has a pair of cables 36 that are operatively supported by cable pulleys 37 on the shafts 34 and 35.

The shaft 34 extends across the space between the main standards 25 and has an 25 extension 38 that extends through to the auxiliary standard 26. The cable shaft 34 is driven by means of a pulley 39 on the extension 38 that is connected by a belt 40 with a pulley 41 on the countershaft 42, the 30 said countershaft being operatively connected to the motor 24 by gearing 43.

The right end of the cable conveyer 22 is suspended from the corresponding end of the roller conveyer 21 by means of a yoke 35 device 44 that permits of changing the relative vertical alinement of the said ends for different positions of adjustment of the two conveyers and the cable conveyer 22 is provided at the right end with a horn 40 shaped extension 45 that extends upwardly in curved form above the end of the roller conveyer 21 that serves as an intermediate guide and receiving device for receiving the unloaded pallets 18 from the roller conveyer 21 and delivering them to the cables 36 of the cable conveyer 22.

The conveyer 17 that receives the pallets loaded with bricks from the yard may be in the form of a cable conveyer instead of a 50 roller conveyer, as shown, and has the inner, delivery end positioned intermediate the main standards 25 and pivotally connected to the said standards 25 as shown at 65, Fig. 1, being generally appreciably below the 55 inner end of the adjustable conveyer 21 at all positions of adjustment thereof.

The loaded pallets are delivered from the yard conveyer 17 to the shed conveyer 21 by means of elevating apparatus of special 60 form, comprising a plurality of sets of hanger devices 46 operatively supported by sprocket chains 47.

The sprocket chains 47 are four in number, arranged in two pairs, one pair on each 65 side and separated from the other pair by a

space of suitable width to accommodate the pallet 18 and a hanger 46 on each side thereof.

The hangers 46 are supported in pendent position from the inner end of a short shaft 48 that extends through the two members 47 that compose one of the pairs of the sprocket chains 47, being incorporated in each case in the structure thereof, and they comprise in each case a pendent arm 49 that 75 extends downwardly from the shaft 48 and an inwardly directed platform or base portion 50 that is suitable for engaging with the under side of the end of the pallet 18.

A pair of mating hangers 46 engages with 80 a pallet 18 on the end of the yard conveyer 17 when the sprocket chains 47 are in operation, raises the pallet along the left side of the main standards 25, carries the pallet over the top and then lowers the pallet on 85 the right side, and finally delivers it to the left end of the shed conveyer 21.

The sprocket chains 47 are supported by sprocket gears 51 that are mounted on a lower shaft 52 and an upper shaft 53 that 90 are supported by the main uprights or standards 25. The upper shaft 53 projects into the space between the rear standard 25 and the auxiliary standard 26 so as to serve as the support for the driving gear 54, 95 which meshes with the gear 55 on the upper countershaft 56.

The said upper countershaft 56 is connected with the lower countershaft 42 by 100 means of belt gearing 57.

As described, the motor 24 is operatively connected with the shaft 34 of the cable conveyer 22 and with the elevating sprocket chains 47.

The duplex arrangement of the sprocket 105 gears 47 for supporting the hanger shaft 48 is provided to hold the hangers 46 in proper operating position for engaging with the pallets, as without this provision the hangers would be liable to tilt from the proper 110 position and thus prevent proper operation.

The shaft 30 for the inner end of the shed conveyer 21 may be provided with guide ways 58 for engaging with the ends thereof to hold them in proper alinement 115 and to prevent obstructing the operation of the adjacent parts.

The upper shaft 53, as shown, is surrounded by a sleeve 59 that rotates with the sprocket gears 51 and which is of suitable 120 diameter to permit the hangers 46 to pass freely thereover under normal conditions generally, which, however, in case of a sagging or shifting out of line of the hangers permits the lower ends of the hangers to 125 contact therewith and to be partially supported in passing over the space between the opposed inner sprocket gears 51.

I claim as my invention:—

1. Elevator and conveyer apparatus for 130

brick yards comprising in combination a shed conveyer for delivering loaded pallets for setting and a second conveyer for returning unloaded pallets, a yard conveyer, 5 and means for delivering loaded pallets from the said yard conveyer to the said shed conveyer.

2. Elevator and conveyer apparatus as described in claim 1, and the said second 10 conveyer being in the form of a positively driven cable conveyer.

3. In elevator and conveyer apparatus for brick yards, elevating sprocket chains operatively supported, hangers arranged in pairs for engaging each with one of the ends 15 of a pallet, each individual hanger being supported by the end of a relatively short shaft, and the said sprocket chains being arranged in two pairs with both members of a pair serving as the means of support for 20 the said shaft.

CHARLES ALBIN NELSON.
